AWNNG BLIND

Harold Ruscher, Mount Vernon, N. Y.

Application December 4, 1935, Serial No. 52,745
Renewed December 28, 1938

20 Claims. (Cl. 189—55)

This invention relates to devices of the nature of blinds and shutters, especially to blinds and the like characterized by a multileaf structure, and more particularly to a blind of the general 5 type commonly known as a "Venetian blind", in which the leaves are supported in spaced relation upon flexible cables or tapes and may be tilted from a closed position, in which their margins overlap tightly, to any of several positions in 10 which the leaves may be selectively arranged in more or less parallel transverse disposition, and therefore are less obstructive to light and air, in proportion to their approach to a spaced parallel plane relation.

15 The primary object of the present invention is to provide a blind structure comprising a set of tilting leaves or slats made wholly or in part of metal or other non-inflammable material, as for example Bakelite, Formica, shatter-proof 20 glass, etc., the leaves having their longitudinal margins adapted to interlock when overlapped, so that the faces of the blind may be respectively continuous from top to bottom when in the extended position of the device.

25 Another object of the invention is to provide 30 means for supporting such a shutter or blind, when the leaves are in their closed, interlocking relationship, in a position in which the blind extends downwardly and outwardly from its upper edge, at which it is movably attached to an overhead member of a window frame, doorway, or like structural opening, to its lower edge, at which region the blind is maintained at a distance from the window sill, so that the device 35 will serve as an awning possessing unusual strength and fireproof characteristics, by reason of its component material.

A cognate object of the invention is to provide 40 flexible connecting and operating cables by which the metal leaves of which the awning is constituted may be raised to a collapsed overhead position by simple draft upon the appropriate cables, and will be nested there under a suitable canopy, without requiring for the operation a degree of 45 skill or training other than that which may be reasonably expected from a shop assistant or household servant of average mentality and experience.

50 A further object is to so organize the interlocking leaves and their supporting cables that the simple release of the appropriate cables is followed by the automatic descent of the leaves and their supporting frame, (which may be of substantially conventional awning-frame structure), to an extended position in which the adjoining margins of the leaf components assume 55 self-engaged interlocking positions without directive effort on the part of the operator.

Still another object is to provide such an arrangement of the leaves and their supporting

and actuating cables that when the blind components have thus descended into their interengaged assembled position, the entire assembly may be swung bodily around its support to bring the free end inward against an 5 upright wall or other structural abutment, and means are provided to secure the device there, in position to act as a fireproof metal shutter or closure for the window, door or other opening, being also substantially weatherproof, vermin- 10 proof, windproof and preventing unauthorized access to the building so protected.

Among other objects is the provision of a novel combination of locking and unlocking cables, these being of such structure, and equipped with 15 such attachments, that when the leaves of the structure are in their interlocking awning position an operator can by simple draft upon the appropriate cables unlock the leaf margins, and then tilt all of the leaves simultaneously, and in 20 a unitary operation, to relatively open positions in which access will be given to desirable circulation of air, and to entry of light, as for example to light a store window, or a dwelling room or office, while the device excludes unduly strong 25 currents of air or undesirable heat rays, etc.

It is also an object of the invention to form the component elements of the entire improved blind or shutter out of non-inflammable material, including not only the slats and their framework, 30 but also the operating cables, so that there is a complete elimination of fire-hazard, and more particularly of that form of fire risk due to the practice of throwing unextinguished matches, lighted butts of cigarettes, etc. out of windows, 35 which is a frequent source of fires and has led to condemnation by the fire-underwriters of awnings made of inflammable materials.

Other objects and advantages will appear as 40 the description of the particular physical embodiment selected to illustrate the invention progresses, and the novel features will be particularly pointed out in the appended claims.

In describing the invention in detail and the 45 particular physical embodiment selected to illustrate the invention, reference will be had to the accompanying drawings and the several views thereon, in which like characters of reference designate like parts throughout the several views and in which:

Figure 1 is a view in side elevation of a blind or shutter structure in the construction of which this invention has been embodied, the same being illustrated in operative position as an awning, with associated building structure and a canopy 55 shown in section; Fig. 2 is a view of the same in front elevation with the canopy shown in vertical, longitudinal section; Fig. 3 is a fragmentary, detail view taken from a similar viewpoint to that of Fig. 1 but with the unlocking means 60

in course of operation; Fig. 4 is a similar view to Fig. 1, but showing leaf components unlocked and tilted to relative positions in which they occupy spaced, approximately parallel planes and afford spaces for the passage of light and air to the protected building aperture; Fig. 5 is a view in vertical section, taken on the medial, vertical plane of Fig. 2, but showing the components of the device retracted to a position above the window and covered by the protective canopy there shown; Fig. 6 is a view from the same front elevational point of view as Fig. 2, but illustrating the improved structure in use as a shutter; and with the canopy shown in section; Fig. 7 is an end elevation of the structure shown in Fig. 6, the canopy being shown in section; Fig. 8 is a fragmentary detail view in perspective illustrating the end and marginal structure of one of the component leaves; Fig. 9 is a fragmentary detail view in vertical section, taken on the line IX-IX of Fig. 6, the arrows at the ends of the line indicating the direction in which the view is taken.

In the now-preferred embodiment of the invention selected for illustration and description, the elements designated respectively by the reference characters 11, 12, 13, 14 and 15 are leaf components of a blind or shutter structure, and while five are shown, any other suitable number either more or less, may be organized to operate in the embodiment of the idea of means herein disclosed, and the size and relative proportions of these leaf components are also susceptible of considerable variation, as well as their structural details.

In pursuance of the invention, these leaves are designed to be assembled with their contiguous transverse flanged edges 16, 17 arranged in interlocking engagement at times, and are so illustrated in the positions shown in Figs. 1 and 2, while Fig. 8 shows, on a larger scale, a particular physical embodiment of the means by which the interlocking action may desirably be carried into effect. The leaf component selected as typical is that numbered 12, and it may be regarded as representing exactly the structure of any of the leaves in this, or any similar embodiment of the invention, other than the end leaf to be described hereinafter.

In accordance with one of the most important objects of the invention, I prefer to provide, as already mentioned, an all-metal structure or a structure made entirely of non-inflammable material for the sake of insuring a completely fire-proof characteristic for this device, and this may be most conveniently realized in the multileaf structure by making each leaf out of sheet metal, for example sheet steel, or other non-inflammable sheet material, each of the leaves illustrated being made from an integral blank of that material in the instance shown, for convenience and economy in fabrication as well as for strength.

For a similar reason and to promote standardization of these important parts, each leaf has what may be termed an "upper" flange 16, and a "lower" flange 17, bent symmetrically in opposite directions from the body 12 of the leaf, with respect to the plane of which body the flanges stand respectively at an angle of somewhat less than 90 degrees, say from parallel relation to 80 degrees, the purpose of this inclination being to cause a firmly retentive hooking effect all along the contiguous edges of adjoining leaf components, while permitting some variation in the catenary curve of the awning from the rather flat catenary arc shown in Fig. 1.

This figure represents the normal effect of gravity when several leaves are hooked together and supported at two remotely spaced fixed points, as at the points 19, each of which designates a region of swinging support of the uppermost leaf 11 from eyes 36, 39, 47 in the lintel of a window frame F of conventional structure, the means for said swinging support to be described later in this specification, and at a lower region where the device includes an awning frame member or members 21, which are of conventional form, in the instance illustrated, being held away from the wall W by awning frame members or struts 22 of known structure. These are of metal and are carried pivotally by slides 23 fitted loosely upon upright metal guide rods 24 attached by screws 25 to the window frame F. The awning frame thus constituted, with its cross-piece 21, struts 22 and the lowermost leaf component 15, is anchored by guys or hold-down cables 26.

Such is the retentive character of the inter-engaged flanges 16, 17, that the leaf structure already described, with its uppermost leaf 11 supported swingingly as at 19, and with its lowermost leaf component 15 connected at its lateral margins to struts 22, as at 21, would quite possibly serve as a self-contained, self-supporting unitary awning structure even in the absence of the further improvements of structure hereinafter disclosed, and as the foregoing multi-leaf awning is novel, so far as I am informed, my claims are to be construed as covering generically this improvement unless specific limitations are intentionally pointed out in particular claims intended to cover more detailed features of the invention.

It may be noted at this stage of my present disclosure that, without any addition of means to effect manipulation of the awning already described, the multileaf structure may be swung around its upper edge, as at 19, into an upright position flat against the window frame F, and will then act as an all-metal shutter to completely close the wall opening surrounded by window frame F; in which position the hook-joints 16, 17 are equally as effective, if not more so, than when acting in the catenary curve relationship described with reference to the structure of Figs. 1, 2, etc.

Such a vertical shutter position is illustrated clearly in Figs. 6 and 7, and is made the subject of specific claims, as well as being covered generally. The upwardly sliding action of the slides 23 in bringing about such an action is of known character, and does not require labored exposition.

The shutter may be fastened in this position by firmly tying the stay rope 26 through an eye, such as the eye 57 mentioned below, on the sill, or if desired, an additional means for locking the shutter in this position may be provided, as for example, a locking means which takes the form of a padlock 54 having a ball 55 engaged with suitable eyes 56, 57, as shown in Fig. 9, the eye 57 being set in the window sill S, and the eye 56 being mounted on one of the leaves, as for example the leaf 15.

In further pursuance of the invention, provision is made of means adapted to operate or co-operate for disengaging the interengaged leaves, and for re-engaging them, also means for raising the assembled multileaf structure to a collapsed position, retracted above the window and out of the way when the device is not in use as an awning or as a shutter.

As has been already foreshadowed, the pre-

ferred means for this purpose comprises a series of flexible wires, strands or cables, in duplicate sets, of which one set is provided at or near each end of the leaves, and each comprises a cable 30 designed primarily for maintaining the leaf components in their general assembled relationship at all times, and which also acts positively, when drawn upon, to raise the leaves to nested position, this retractive action beginning with the 10 lowermost leaf 15, through which the cable 30 extends, having an enlargement 31 which is engaged with the under surface of leaf 15.

From this point of attachment with the leaf the cable 30 then extends through an opening 32 in the next leaf 14, and similarly through a like opening 33 in leaf 13, opening 34 in leaf 12, and opening 35 in leaf 11, from which latter the cable extends through an eye 36 attached to the wall W as shown in Fig. 4, and downward along the frame 20 of window F to a cleat 37, upon which its free end may be made fast and its slack accumulated, as indicated in the drawings.

In further pursuance of the invention, a flexible cable is provided for effecting the unlocking of 25 the interlocking margins 16, 17 of the leaves when it is desired to tilt them to such an open position, for example, as that shown in Fig. 4. For this

purpose sets of cables 40 are provided, one preferably near each margin of the leaves, the reference character 40 designating these sets of cables generally, and each set comprising a lower stretch 41, the upper part of which is knotted, as at 42, in a lug 49, one at each upper corner of the leaf 11, while an upper stretch 43, in continuation 35 integrally of the stretch 41, forms a bight or loop B, the cable extending through an orifice 44 in the leading margin 45 of the leaf 15 (see Fig. 2) so that the leaves 11, 12, 13 and 14 move upward when draft is exerted upon an extension 46 of the 40 stretch 43 (see Fig. 4). This extension passes through an eye 47 fixed in the window frame F, and a cleat 48 is provided to receive the free end of the extension 46.

As shown clearly in Fig. 4, the cable stretch 41 runs through apertured lugs 49 similar to that already mentioned, one of these lugs being formed on the edge of each leaf adjacent to the slots 31 to 35 respectively. One of these lugs is shown in greater detail in Fig. 8, adjacent to the orifice 34 in leaf 12. This leaf, and each of the other leaves, is provided also with an apertured lug 50, and through this series of lugs is threaded the stretch 43 of the cable 40.

The stretches 41 and 43 have been devised by 55 me to cooperate in exerting first an unlocking action and then a tilting action upon the leaves, progressively, beginning with the lowermost leaf 15, and this combined and progressive series of actions is accomplished by novel means comprising a series of enlargements 51 to 53 inclusive, such as the shot like elements illustrated, which are fixed upon the stretch 43, each at a point where it is adapted to be engaged eventually with one of the lugs 50, in the manner best shown in 60 Fig. 3, where the spacing of the shot is illustrated in detail.

In the last named figure, the parts are shown in the position which they assume relatively to each other just after the operator has begun to 65 pull down upon the cable extension 46 for the purpose of tilting the leaves from the position shown in Fig. 1 to that shown in Fig. 4. In the Fig. 1 position, it will be noted that shot 51 is at a slight distance from its neighboring lug 50 on leaf 14, while shot 52 is at a greater distance from

its neighboring lug 50 on leaf 13 and shot 53 is at a still greater distance from its neighboring lug 50 on leaf 12.

In the Fig. 3 position, the pull by the operator upon the cable stretch 43 has first drawn its 5 bight B through orifice 44, thus tilting the leaf 15, and unhooking the flange 16 at the upper margin of leaf 15 from the contiguous flange 17 at the lower margin of the adjoining leaf 14.

Thereafter, the leaf 14, being thus freed at its 10 lower end, is advanced upwardly by the action of shot 51 upon its lug 50, so that the articulation 16, 17 between leaves 14 and 13 is broken, as indicated in Fig. 3, and by a slight further draft upon stretch 43 from the position shown in Fig. 15 3, the articulation 16, 17 between leaves 13 and 12 will be similarly broken, by action of shot 52 upon the lug 50 of leaf 13, and in due course the shot 53 will engage lug 50 upon leaf 12 and break its articulation with leaf 11. Finally, the operator, by suitable drawing upon extension 46, can tilt the leaves simultaneously to any suitable position of substantial parallelism in spaced planes, as in Fig. 4, and by making fast the extensions 46 and 46a upon cleat 48, can insure the 20 maintenance of the parts in selected adjustive position.

Conversely, upon exerting draft on the extension 46a of cable 40, the parts will be returned to the Fig. 1 position, which is the normal awning 30 position, this return being assisted by gravity, and at any time the parts can be retracted from this position to the overhead position of Fig. 5 by simply loosening the hold-down stay 26, pulling down the cables 30 to raise the leaves, and making 35 fast upon the cleat 37 the raising cables, of which there are preferably two, one at each side of the structure, the reference character 38 in Fig. 7 indicating the usual cross-over position of one of the raising cables 30, after it has passed 40 through the eye 39 on its way to eye 36. By manipulation of the cables 41, 43, the leaves may be adjusted to any desired angular position, from the uniplanar relation to that of complete parallelism with each other.

The leaves 11 to 15, when thus retracted, are compactly nested above the level of the window frame F, as shown in Fig. 5, and may be there 45 protected and hidden by a canopy C.

The weight of the nested leaves is largely borne 50 in this retracted position by the cables 30, these acting also at such time as a tie-back to prevent unintended descent of the device. In this position, the short vertical stretch of the cables 30 is favorably disposed to perform this service. 55 Neither in this position nor in the normal awning position of Fig. 1, nor in the upright shutter position of Fig. 7, is undue strain placed upon the cables 30, as in both of the lowered positions the articulations 16, 17 between the successive 60 leaves sustain the weight of the structure in a manner for which the metal hook-joint formation qualifies them amply; and even during the operation of lifting the leaves to the nested position it will be noted that they are initially supported partially by the struts 22. The diminishing angle of displacement of these struts from the vertical as the weight supported thereby increases, provides for a compensatory modification of the moment of lifting force demanded of 70 the cable 30, until the retraction reaches a point where the slides 23 of the struts are drawn upward from the position shown in Fig. 5.

From the foregoing disclosure it will be apparent that the novel shutter blind structure illus- 75

trated and described constitutes a complete realization of the first stated objects of the invention, being simple and sturdy in construction, easily fabricated, installed and operated; of low maintenance expense, not easily injured or put out of order; completely fireproof, weatherproof and verminproof; readily packed for transportation; useful in any climate; adjustable for control of light and ventilation; capable of receiving advertising media in many forms; readily repaired; and adapted to be made largely of parts already stocked by manufacturers and dealers.

If the leaves be fabricated with transparent panels, as for example of shatter-proof glass, the structure may be utilized to great advantage as a storm window. It may also be used with suitable inclusions of glass prisms to reflect light into interiors from an exterior light-source.

Interior partitions may be fabricated advantageously in a manner similar to that shown in Figs. 6 and 7. The use of struts 22 would not be essential for such partitions, and in various other applications of the device.

Although I have particularly described particular physical embodiments of my invention and explained the operation, construction and principle thereof, nevertheless, I desire to have it understood that the forms selected are merely illustrative, but do not exhaust the possible physical embodiments of the idea of means underlying my invention.

What I claim as new and desire to secure by Letters Patent of the United States, is:

1. A leaf structure of the nature of a Venetian blind, comprising leaf components connected together by flexible elements and characterized by marginal flanges adapted to constitute complementary interlocking means when brought into contiguous relation along adjoining edges of said leaves in a joint disposed transversely of the blind in its extended position, and means adapted respectively to move said leaves to unlock said adjoining flanges and to tilt said leaves to non-contiguous positions with spaces therebetween.

2. A multileaf structure comprising leaf components and flexible connecting elements combined and cooperating as set forth in claim 1, and further characterized by having each of said leaf components formed as a unitary structure of sheet metal and by having said flexible connecting elements formed of wire strand, and means whereby said structure may be locked flat against an opening in a building at will to form a fireproof closure, and may be unlocked and removed from said position of closure, at will.

3. A multileaf structure of the nature of a Venetian blind, comprising several leaf components adapted respectively to be disposed in positions with open spaces between neighboring leaves, and connected together by flexible elements and characterized by marginal flanges adapted to constitute complementary interlocking means when brought into contiguous relation along adjoining edges of said leaves in a joint disposed transversely of the blind in its extended position, and further characterized by having said leaf components and flexible elements formed of metal throughout said multileaf structure; and means adapted to unlock said flanges and tilt said leaves to said open positions.

4. A multileaf structure of the nature of a Venetian blind, characterized by having a series of tilttable leaves, and flexible suspenders therefor, said leaves being each provided with at least one marginal hook-flange which is adapted to be

articulated with a similar, complementary, contiguous hook-flange on an adjoining leaf component when said hook-flanges are tilted or moved to adjoining positions, and said hook-joints, when so completed, serving as a supporting means throughout the assembly of leaf components so interjoined, for all positions of said multileaf structure in which the force of gravity and/or applied force is effective to maintain said conjoined relationship of said leaves, and means to move said leaves respectively to unhooked positions, and to tilt them to form spaces therebetween.

5. A multileaf structure of the class described, comprising leaf components and flexible supporting cables or tapes therefor, upon which, and by manipulation of which, said leaf components may be tilted relatively to each other through a range of positions, from an end-of-the-range position in which the leaves all lie in substantially the same plane or selectively in the same extended curved surface, forming a catenary curve to an end-of-the-range position in which each of said leaves lies in an individual plane substantially parallel with, and spaced from, the plane of every other leaf, forming selectively a straight or a curved unitary structure, said leaves being further characterized by having means for articulation of said leaves in edge-to-edge relation when occupying said uniplanar position.

6. A multileaf structure of the class described, comprising leaf components and flexible supporting cables or tapes therefor, upon which, and by manipulation of which, said leaf components may be tilted relatively to each other through a range of positions, from an end-of-the-range position in which the leaves all lie in substantially the same plane or relatively in the same extended curved surface, to an end-of-the-range position in which each of said leaves lies in an individual plane substantially parallel with, and spaced from, the plane of every other leaf, said leaves being further characterized by having means for the articulation of said leaves in edge-to-edge relation when occupying said uniplanar position, and also being characterized by means for disjoining said assembly of leaves and for tilting the leaf components respectively, at will.

7. A multileaf structure comprising leaf components and flexible connecting elements combined and cooperating as set forth in claim 1, and further characterized by having said leaves arranged to be unlocked and held in an elevated, nested position, from which said leaves, when released, descend into a self-interlocking relationship.

8. A transversely flexible multileaf structure of the class described, comprising leaf components having interlocking joints along adjoining edges disposed horizontally whereby said conjunctive assembly is maintained by gravity when said conjoined leaves are suspended in closed relationship in a perpendicular position and selectively in any catenary curve.

9. A multileaf flexible structure of the class described, comprising leaf components having interlocking joints along adjoining edges, and manually operable flexible connections whereby said joints may be unlocked at will and said leaves may be tilted relatively to each other and relocked at will.

10. A multileaf structure comprising the leaf components and flexible elements combined and cooperating as set forth in claim 9 and further characterized by having said leaves provided with

orifices and one of said flexible connections threaded through said orifices for holding said leaves in an extended uniplanar assembly, also for holding said leaves in a retracted, nested assembly, and selectively in various intermediate positions wherein said leaves occupy different angular positions relatively to each other; other of said flexible elements being effective at will to unlock, tilt, and relock said leaves.

11. A multileaf shutter-blind-awning structure comprising a series of elongated, broad, metal leaf components, each having a pair of apertured lugs spaced apart at its leading edge, a pair of apertured lugs spaced apart at its leading edge, a pair of apertured lugs spaced apart at its rearward edge, and a pair of slots spaced apart at the end margins of said leaf, said leaf components being threaded upon a system of flexible suspenders passing through said apertured lugs and slots, and adapted for attachment to a building element, and an awning frame connected pivotally to a lower leaf of said series, and adapted to be connected pivotally to said building, said awning frame after such installation, being movable by action of said flexible suspenders to pick up said leaves successively upon said lower leaf while swinging the same through an arcuate path, and being tiltatable to spaced-apart positions by cooperative action of said flexible suspenders at any portion of said arcuate path.

12. A multileaf awning structure comprising several leaf components respectively provided with interlocking flanges along adjoining edges, and a flexible connecting cable formed with stretches united by a loop, in a bight of which loop the lowermost leaf is included for the purpose of unlocking one of said edge joints, one of said cable stretches being provided with means to unlock others of said joints thereby to permit a tilting movement of said leaves relatively to each other induced by relative movement of said cable stretches in opposite directions.

13. A multileaf awning structure as in claim 9, and further characterized by having certain of said leaves provided with lugs, and one of said cable stretches provided with enlargements, such as shot, said lugs and enlargements cooperating to constitute said unlocking and tilting means.

14. A multileaf awning structure as in claim 9, and further characterized by having certain of said leaves provided with lugs, and one of said cable stretches provided with enlargements, said lugs and enlargements cooperating to constitute said unlocking and tilting means, said enlargements being so spaced upon said cable as to act progressively to unlock said joints.

15. An awning comprising an awning frame having means to mount the same upon a building element, a multileaf awning having a leaf component mounted upon the free end of said awning frame, and adapted to swing therewith through an arc from a normally extended position of use to an overhead position of disuse, said awning including also a series of complementary leaves each having interlocking flanges along their contiguous edge joints, and adapted to serve conjointly with said first-named leaf to form said awning when extended, and means to arrange said complementary leaves in horizontally stacked, nested position upon said first named leaf when in said position of disuse.

16. An awning comprising an awning frame having means to mount the same upon a build-

ing element, a multileaf awning having a leaf component mounted upon the free end of said awning frame, and adapted to swing therewith through an arc from a normally extended position of use to an overhead position of disuse, said awning including also a series of complementary leaves adapted to serve conjointly with said first-named leaf to form said awning when extended, and means to arrange said complementary leaves in stacked, nested position upon said first named leaf when in said position of disuse, and a canopy to protect said stack of awning leaves, said canopy having a contour adapted to fit snugly upon said assembled leaves, and thus to afford an abutment against which they may be held free from vibration.

17. A leaf component for multileaf structures of the class described, said leaf component comprising a broad, elongated slat-like body portion formed of sheet material and having a marginal hook-flange along at least one longitudinal edge adapted to conjoin with a similar contiguous hook flange upon an adjoining leaf component of said multileaf structure, said leaf being further characterized by having a pair of spaced apertured lugs adjacent to the respective ends of each of said flanges, and a pair of slots in spaced positions each adjacent to an end margin of said leaf, whereby said leaf is adapted to be fitted with a system of complementary flexible suspenders including a set of such suspenders at each end of said leaf, operating in non-interfering relation with each other.

18. A leaf structure of the nature of a Venetian blind comprising leaf components connected together loosely, permitting limited relative movement therebetween, and having marginal flanges adapted to constitute complementary interlocking means when brought into contiguous relation along adjoining edges of said leaves in a joint disposed transversely of the blind in an extended position thereof, means adapted to guide said leaves into their interlocked relation, and means adapted to move said leaves relatively to each other to unlock said adjoining flanges and to tilt said leaves to non-contiguous positions with space therebetween.

19. A multileaf structure comprising leaf-components of non-inflammable materials characterized by having marginal flanges adapted to constitute complementary flange excluding joints extending transversely of the structure in its extended position; supporting means of non-inflammable material adapted to support the leaves in relatively open and relatively closed positions; and operating means comprised of non-inflammable materials, whereby said leaves may be tilted from an open position to a flame excluding interlocked position; said multileaf structure being so constituted non-inflammable unitary structure for the intended use.

20. A multileaf structure of the class described: comprising leaf components made of relatively light sheet metal; means to support said leaves in Venetian blind relationship; means to tilt said leaves into positions intermediate their extreme open and closed positions; and marginal flanges adapted to effect interlocking engagement of said leaves in their closed positions; said flanges being formed with an adequate projection from the plane of its leaf to render the same substantially rigid in its open positions.

HAROLD RUSCHER.
